Patented Jan. 11, 1966

203,488

COMBINED ADVERTISING DISPLAY CABINET AND WEATHER STATION PANEL

Edward J. Delaney, 666 Temple St., Whitman, Mass.

Filed Dec. 4, 1964, Ser. No. 82,918

Term of patent 14 years

(Cl. D80—11)

Fig. 1.

Fig. 2.

Fig. 3.

Fig. 4.

Fig. 5.

FIG. 1 is a top plan view of a combined advertising display cabinet and weather station panel, showing my new design,

FIG. 2 is a front elevational view,

FIG. 3 is a bottom plan view,

FIG. 4 is a side elevational view, and

FIG. 5 is a perspective view thereof, but on a smaller scale.

The dominant features of my design reside in the portions shown in full lines.

I claim:

The ornamental design for a combined advertising display cabinet and weather station panel, substantially as shown and described.
